UNITED STATES PATENT OFFICE.

GEORGE S. STRONG, OF NEW YORK, N. Y.

ELECTRIC FURNACE.

SPECIFICATION forming part of Letters Patent No. 665,704, dated January 8, 1901.

Application filed April 4, 1896. Serial No. 586,182. (No model.)

To all whom it may concern:

Be it known that I, GEORGE S. STRONG, a citizen of the United States, residing in the city of New York, in the county and State of New York, have invented a certain new and useful Improvement in Electric Furnaces, of which the following is a true and exact description, reference being had to the accompanying drawings, which form a part of this specification.

My invention relates to electric furnaces, and has for its object primarily to provide for the attainment of an exceedingly high temperature in such furnaces. Particularly my invention relates to furnaces intended for the manufacturing of compounds such, for instance, as calcium carbid and in which some or all of the ingredients of the furnace charge are fed to the furnace in the form of electrodes, preferably formed and fed to the furnace from a plastic mass of the material, my present invention being in part an improvement upon the invention described and shown in my former Letters Patent, No. 587,343, of August 3, 1897.

The nature of my improvements will be best understood as described in connection with the drawings, which illustrate a furnace and devices used in connection therewith, which embody my improvements, and in which—

Figure 1 is a sectional elevation; Fig. 2, a plan view of a detail of the feeding mechanism; Fig. 3, an end view of the furnace, showing a certain portion of the feeding mechanism in section. Fig. 4 is a cross-sectional view taken on the line 1 1 of Fig. 3. Fig. 5 is an elevation, partly in section, of the governing mechanism. Fig. 6 a plan, partly in section, of the valve and valve-actuating devices forming part of the governing mechanism; and Fig. 7 is a detail of the device for throwing fuel and air into the enveloping multiple A¹².

A is the furnace proper, which is of a type adapted to be heated by means of the electric arc. As shown, the top of the furnace (indicated at A') is arched, so that the heat will be reverberated from it to the part of the furnace where the greatest intensity of heat is required. The lower part A² of the furnace is intended to serve as a receptacle for the calcium carbid or other material resulting from the treatment of the charge in the upper

part of the furnace. The bottom A³ of the furnace is made movable, so that the accumulation upon it can be removed from time to time into the receiving-chamber A⁴. It is important for the best results that air should be excluded or substantially excluded from the furnace A, and at the same time it is necessary to provide means for drawing off the gas generated in the furnace, and this I do in the plan shown by means of the flared-mouthed passage A⁵ in the crown of the furnace, this passage leading to a chamber A⁶, from which chamber leads a pipe A having, as shown, branches A⁸ and A⁹, controlled, respectively, by valves a⁸ and a⁹. The branch A⁸ may lead to the atmosphere or into any convenient device for storing or utilizing the gases. The branch A⁹, however, leads, as shown, through an open-ended pipe A¹⁰ to a nozzle or nozzles A¹¹, which in turn lead to an enveloping muffle A¹², which last-mentioned muffle encloses as much of the furnace A as is practically convenient, A¹³ representing the escape pipe or stack of the muffle A¹², and a¹² indicating extensions of the muffle A¹² the function of which will be hereinafter described.

B is a pipe through which liquid fuel is led to a nozzle B², B' being a pipe by which compressed air is forced to the nozzle B³, lying within the nozzle B². The nozzle B² is entered into a flared extension a¹¹ of the nozzle A¹¹, and this flared extension a¹¹, as well as the nozzle B², lies in a conduit B⁴, into which conduit open the pipes A⁹ and A¹⁰. It will be understood that oil or gas introduced through the conduit B and mixed with air from the conduit B' will be thrown into the muffle A¹² and ignited therein, thus heating this muffle and through the inner walls thereof heating the furnace A, which furnace A is at the same time internally heated by the electric arc. Obviously an exceedingly high temperature is obtainable in the furnace A by this means, and this is the prime object of my invention. Obviously also the valve a⁸ being closed and the valve a⁹ being open, the gases generated in the furnace A will pass, through the conduit A⁵, the chamber A⁶, and the conduits A⁷ and A⁹, to the conduit B⁴ and thence through the nozzles A¹¹ into the muffle A¹², where they may serve as fuel for the said muffle, and at the same time the air nec-

essary to support combustion in the muffle is drawn in through pipe A¹⁰, preheated by contact with the pipe A⁹, and passed thence through the conduit B⁴ and nozzles A¹¹ to the muffle A¹².

d indicates a sight-hole leading into the furnace opposite to the point where the arc is formed.

C indicates a receptacle having a hopper-shaped bottom C', the opening of which lies directly above the flared mouth of the opening A⁵, C² representing a conical valve by which this opening is closed or regulated, and C³ a valve-regulating wheel. Material to be treated is supplied to the receptacle C and fed at any desired rate of speed into the furnace A. I believe this device for feeding the furnace will be found convenient at times; but I contemplate its use principally as an adjunct to the method of feeding the furnace to be hereinafter described.

D are electrode-guides, which should be made of material sufficiently refractory to resist the intense heat of the furnace and a material which is a good conductor of electricity. Preferably they are made of hard carbon.

E E are metal sockets in which the electrode-guides D are secured. As shown, these sockets are made hollow, and I preferably form them of iron. E' and E² are pipes connecting with the hollow sockets E at top and bottom and in communication with a water-tank E³. Water is forced through one pipe through the socket E and back through the other pipe by any convenient pump or equivalent device, and the sockets are thus kept cool. The pipes E' and E² serve also as conductors for the electric current, which passes, for instance, from a connection F through both pipes to the socket E and from the socket E to the guide D. The current delivered to the one guide is positive and the current to the other guide negative.

G G are conduits or guides for the electrodes, made up of some highly-refractory material, such as brick, communicating, as shown, with the electrode-guides D D and preferably surrounded by the muffles A¹² a¹², which are preferably in communication with and form a part of the muffle A¹².

H H indicate metallic electrode-guides lying flush with the outer ends of the guides G G and flaring outward, so that their outer ends lie flush with a cylinder I, with which they are in communication.

H² H² are feeding and pressing rollers which project into the narrower part of the flared portion H' and are geared together by means of the pinions h² h², driven by the worm-wheel H³, which is secured on the end of the shaft U².

I' I' are hoppers through which material is fed to the outer end of the cylinder I.

J is a feed-screw working in the cylinder I and acting to force the material from the hopper I' into the said cylinder and thence through the flared mouthpiece H' into the

guide H and thence through the guides G and D into the furnace A, the rollers H² acting to compress and solidify the material as it passes from the cylinder to the electrode-guide.

J' is the shaft of the feed-screw J, to which is secured the worm-wheel J², driven by a worm J³, secured to the shaft J⁵, to which shaft is also secured the pinion J⁴. This pinion is driven by a pinion K², journaled on the shaft K, which in turn is driven by a motor, an electric motor being indicated, one at K' and the other at k', and these motors, I will state, are arranged to run at different speeds corresponding with the consumption of the positive and negative electrodes in the furnace and so as to feed each electrode with a speed corresponding to its consumption. 85

K³ indicates a projecting hub of the pinion K², upon which hub is secured an annular friction-surface K⁴.

L is a clutch-supporting block having projecting arms L' L', (see Figs. 3 and 4,) L² being a cylindrical jacket around the clutch, the clutch being keyed to the shaft K, as indicated at L³.

L⁴ is a clutch-band lying in the cylindrical hollow of the clutch-block L and around the friction-surface K⁴. The two ends of this clutch-band or friction-band are engaged by clutches L⁵ L⁵, each pivotally secured to set-screws l' and actuated by the wedge-shaped end of the pivot-lever L⁶, said lever being pivoted at L⁷ and the link end L⁸ actuated by a link L⁹ with a sliding collar L¹⁰, the movement of this clutch along the shaft K being effected by its engagement with the arm L¹¹ with a lever pivoted at L¹², and the other arm L¹³ of which is actuated through the bell-crank lever M M', pivoted at M² by the rod M³. Each of the rods M³ is connected with the arms N of the bell-crank levers N N', pivoted at N² N² and normally forced outward by the action of the springs N³ N³. (See Fig. 5.) The arms N N' of the levers are connected by links O O with the pivot-pin O' of a piston O², working in the cylinder P and connected through a port P' with the valve-box Q. (Best shown in Fig. 6.) The valve-box Q is provided with an entrance-port Q' for fluid under pressure, communicating with a chamber Q² of the box, provided in addition with a chamber Q³, communicating with the chamber Q² through passage q², chamber Q³ communicating through passage Q⁴ with the port P', and the chamber Q⁵ communicating through port q⁵ with the chamber Q⁶, which chamber is in communication with the exhaust-passage Q⁷. 115

Q⁸ Q⁸ indicate spring-boxes screwing into the valve-box, as indicated. 120

R and R' are valves adapted normally to close the ports q³ and q⁵. By means of projections R² R² on the valve-stems they are actuated upon by the springs R³ R³, so as normally to keep them closed, and the valve-stems (indicated at R⁴ R⁴) project from the other end of the valve-box and are provided

with heads R^5 R^5 , which heads rest upon or in close proximity to the oppositely-projecting arms S and S' , which are secured to a sleeve S^2 and journaled on a shaft S^3 , the sleeve S^2 being also connected with a long lever-arm S^4 , which is connected, by means of the links S^5 S^5 , with the pivot-pin T of a rod T' , the outer end of which, T^2 , is supported by a rigid slide and which carries a solenoid-core T^3 , the solenoid-coil being indicated at T^4 as secured to a rigid part of the framing (indicated at T^5), T^6 being an adjustable thimble screwing into the framing T^5 and carrying the spring T^7 , which acts to thrust the solenoid-core T^3 out of the coils T^4 and to hold the arms S and S' , normally in the position indicated in Fig. 6. It is obvious, of course, that by passing a current through the solenoid-coil T^4 the core will be attracted and acting on the rods and levers connected therewith will raise the arm S and depress the arm S' , thus permitting fluid under pressure to enter through port Q' , pass through chamber Q^2 , port q^2 , chamber Q^3 , and ports Q^4 and P' to the cylinder P , where it will depress the piston O^2 and acting through the bell-crank levers N N' and the connecting system described will move the sleeve L^10 outward and by its means acting through the lever L^8 L^6 regulates the pressure which keeps the friction-band L^4 in action, and thus disconnect the pinion K^4 from operative connection with the shaft K , stopping the feeding mechanism. On the other hand, the diminution or cessation of current through the solenoid-coils will permit the spring T^7 to force the core T^3 out of the coil, this action involving the closing of the valve R and the opening of the valve R' , whereupon the fluid is permitted to escape from piston P through ports P' and Q^4 , chamber Q^5 , port q^5 , chamber Q^6 , and exhaust-passage Q^7 , whereupon the springs N^8 N^8 will at once cause the arms N N' of the levers N N' to move outward and acting through the described connections will reengage the clutch, coupling the pinion K^2 to the shaft K and setting the feeding mechanism into operation.

It will be understood that the current which actuates the solenoid-coil T^4 will be regulated in any of the well-known ways by the resistance developed to the passage of the arc between the electrodes in the furnace A .

The material fed to the hopper I' may be made up of a mixture comprising all the ingredients of the charge to be treated in the furnace or of only some of these ingredients, the other ingredients being fed or supplied to the furnace in some other way. The mass is to be of such a character that it will be aggregated or solidified by pressure or by the action of pressure and heat, to both of which it is subjected before reaching the furnace. It is fed continuously through the cylinder I through the flared mouthpiece H' , passing the rollers H^2 and then passing through the guides H , G , and D into the furnace, being

subjected while passing through the guides G to a very high temperature derived from the muffle a^{12} , and thus reaching the furnace already heated and very highly heated, so that the additional heat developed by the are springing from one electrode to the other will be sufficient to effect the desired chemical combination with great rapidity.

While I desire to make my electrodes proper as highly conducting as possible, it will be apparent that their conductivity will necessarily be much lower than that of carbon electrodes, and therefore it is that I find it advisable to use the electrode-guides D , made of some highly-conducting material, such as carbon, and projecting into the furnace, so as to give free way to the ends of the electrodes when in proper position for the formation of the arc. By this means I diminish very greatly the distance through which the electric current must traverse to the electrodes proper.

It is of course apparent from what has already been said that the heat to which the furnaces and the electrodes made up of the material of the charge are subjected is by my arrangement of the utmost possible intensity, the electrodes not only being highly heated before entering the furnace, but the furnace being heated not only by the intense heat of the electric arc, but by the great heat developed in the enveloping muffle A^{12} and communicated through its walls to the inner furnace.

Having now described my invention, what I claim as new, and desire to secure by Letters Patent, is—

1. A furnace as A , in combination with a conduit or conduits, as G , leading into the furnace adapted for the feeding in of the material to be treated in the form of an electrode or electrodes, one or more muffles, as a^{12} , surrounding said electrode conduit or conduits, independent means for heating said muffles and means for heating the furnace A by the electric arc including an electric circuit or circuits whereby current is conveyed to the electrodes in the conduits G .

2. A furnace as A in combination with means for heating the furnace internally by the electric arc, a conduit or conduits as G leading into the furnace adapted for the feeding of the material to be treated, one or more muffles as A^{12} a^{12} surrounding said furnace A and said conduit or conduits G and independent means for heating the same.

3. A furnace as A in combination with means for heating the furnace internally by the electric arc, an enveloping muffle as A^{12} , means for heating said muffle independently and by combustion and a conduit leading from the interior to the enveloping muffle whereby gases generated in the electrically-heated furnace are led to the enveloping furnace and used for heating the same.

4. A furnace as A so constructed as to exclude air therefrom when in operation in combination with means for heating the furnace

internally by the electric arc, an enveloping muffle as A¹², means for heating said muffle independently and by combustion and a conduit leading from the interior to the enveloping muffle whereby gases generated in the electrically-heated furnace are led to the enveloping furnace and used for heating the same.

5. A furnace in combination with electrode-guides as D D formed of refractory and conducting material and extending into the furnace, electrical connections to each said guide, means for forcing into the furnace electrodes made up of an aggregated mass of some or all 10 of the ingredients of the furnace charge and independent means for raising said electrodes to a high temperature situated adjacent to the furnace.

6. A furnace in combination with electrode-guides as D D formed of refractory and conducting material and extending into the furnace, electrical connections to each said guide, means for forming and forcing into the furnace electrodes made up of an aggregated 15 mass of some or all of the ingredients of the furnace charge and means for raising the said electrodes to a high temperature situated between the forming mechanism and the furnace.

20 7. A furnace in combination with means for forcing into the furnace electrodes made up of an aggregated mass of some or all of the ingredients of the furnace charge, hollow sockets E at the end of the conduit through 25 which the electrodes enter the furnace, water-pipes leading to and from said sockets and car-

bon electrode-guides D seated in said sockets and projecting into the furnace.

8. A furnace in combination with means for forming and forcing into the furnace electrodes made up of an aggregated mass of some or all of the ingredients of the furnace charge, hollow sockets E at the end of the conduit through which the electrodes enter the furnace, water-pipes leading to and from said 40 45 sockets and carbon electrode-guides D seated in said sockets and projecting into the furnace.

9. The combination with an electrically-heated furnace as A, of an inclosing muffle 50 as A¹², a conduit leading from the electrically-heated furnace to the inclosing muffle whereby the gases generated are led into the outer muffle, an air-supply pipe for the outer muffle arranged to inclose a portion of the said conduit and means for injecting fluid fuel and air into the enveloping or outer muffle.

10. In combination with an electric furnace, means for forming and feeding electrodes made up of a mass of plastic material 60 into the furnace, independent mechanism for actuating said forming and feeding devices so that the electrodes can be supplied to the furnace at a speed proportioned to their consumption therein and governing mechanism 65 for the forming and feeding mechanism whereby the independent mechanisms are stopped and started simultaneously.

GEO. S. STRONG.
